Primary Examiner—Wallace R. Burke*Assistant Examiner*—M. H. Tung*Attorney, Agent, or Firm*—Lockwood, Alex, FitzGibbon & Cummings[57] **CLAIM**

The ornamental design for a water filter cover, as shown and described.

DESCRIPTION

FIG. 1 is a perspective view of a water filter cover showing my new design;

FIG. 2 is a side elevational view thereof, the opposite side is a mirror image;

FIG. 3 is a rear elevational view thereof; and,
FIG. 4 is a top plan view thereof.

The broken line drawing of a water filter in FIGS. 1-3 is for illustrative purposes only and forms no part of the claimed design.

FIG. 1

FIG. 2

FIG. 3

FIG. 4
